UNITED STATES PATENT OFFICE.

JOHN JOHNSON, OF EAST ALTON, ILLINOIS.

WASHING MACHINE.

1,425,204.

Specification of Letters Patent. Patented Aug. 8, 1922.

Application filed October 11, 1920. Serial No. 416,068.

To all whom it may concern:

Be it known that I, JOHN JOHNSON, a citizen of the United States, residing at East Alton, in the county of Madison and State of Illinois, have invented certain new and useful Improvements in Washing Machines, of which the following is a specification.

My present invention relates to improvements in washing machines, and is a distinct and practical improvement to overcome certain practical objections to, and defects in, the present forms of reversing mechanism now employed in washing machine construction.

An object of the invention is the provision of means for automatically reversing the rotary movement of the clothes receptacle after a predetermined number of revolutions thereof in one direction.

With the above and other objects in view, the invention consists in the novel features of construction, arrangement and combination of parts hereinafter described and finally pointed out in the claims hereto appended.

Referring to the accompanying drawings forming a part of this specification wherein like characters of reference denote similar parts throughout the several views:

Fig. 1 is a plan view of my improved washing machine.

Fig. 2, is a side elevation thereof.

Fig. 3 is an end elevation of the washing machine looking at the end thereof which is provided with the reversing mechanism.

Fig. 4, is a detail, mostly in sectional elevation, showing the valve arrangement for introducing air into the water of the clothes receptacle for lifting and loosening the clothes at the bottom of the receptacle.

Fig. 5, is a view taken on line 5—5 of Fig. 1.

Referring to the drawings, the reference character 1 indicates a suitable cylindrical tank, or tub which is supported at either end by means of suitable supporting legs 2. The upper part of the tank 1 is provided with an opening which is closed by means of a suitable door 3.

4 indicates a cylindrical clothes receptacle. A supporting drive shaft 5 is fixed to one end of the clothes receptacle 4 and is journaled in a suitable bearing 6 carried by one end of the tank, or tub 1. The opposite end of clothes receptacle 4 is pro-

vided with a suitable bearing 7 in which bearing is journaled a suitable spindle 8. The spindle 8 is suitably fixed to one end of the tank 1. This arrangement rotatably supports the clothes receptacle 4 within the tank 1, as is manifest.

The means for imparting reversible rotary movement to clothes receptacle 4, within the tank 1, will now be described.

A suitable gear 9 is fixed to the supporting drive shaft 5. The gear 9 meshes with a pinion 10 fixed to a driven shaft 11, which shaft 11 is journaled in suitable bearings 12 which are preferably united, although not necessarily so, and which are provided with a suitable supporting leg 13.

14 indicates a fixed pulley mounted upon the driven shaft 11, while 15 and 16 indicate loose pulleys mounted upon the driven shaft 11 on opposite sides of the fixed pulley 14, as clearly shown in Fig. 1. 17 indicates a belt which runs in one direction, and 18 indicates a belt which runs in the opposite direction. The belt 17 rides over the loose pulley 15 when not riding over the fixed pulley 14, and the belt 18 rides over the loose pulley 16 when not riding over the fixed pulley 14, as is manifest. 19 indicates a belt guide which controls the sliding movement of belt 17, while 20 indicates a belt guide which controls the sliding movement of the belt 18.

The upper end of the belt guide 19 is fixed to a movable, or shifting plate 21. This plate 21 is slidably supported in a suitable manner by means of the hangers 22, which hangers are fixed to and depend from a suitable bracket 23 that is suitably fixed at one end to one end of the tank, or tub 1. The belt guide 20 is pivotally connected near its upper end to a suitable bracket 24 which, in turn, is suitably fixed to the movable plate 21. The upper end of the belt guide 20 is provided with a suitable handle 25 for shifting the belt 18 by hand, when so desired, such as for actuating a wringer, as will be set forth hereinafter. The belt guide 20 is locked in its desired position, by any suitable means, such for instance as a pin 26 passing through an opening in the belt guide 20 and the supporting bracket 24.

27 indicates a movable rack member having the cutaway portions 28 to form shoulders 29 at each end of each cutaway portion. 110 The rack member 27 is slidably mounted at each end in suitable bearings 30, which

bearings are suitably fixed to the end wall of the tank, or tub 1, as shown.

A suitable pin, or projection 31 is fixed to the hub of the gear 9 and enters the 5 cutaway portions 28 of the rack member 27 to engage the shoulders 29 in its rotary movement, thereby moving the rack member 27 a predetermined distance in the same direction as the travel of the pin 31, as is 10 manifest. When the rack member 27 has traveled a predetermined distance in one direction, to the right as an illustration, the rack member 27 will engage and move the end 32 of a suitable bell-crank 33 which 15 works in a slotted opening 34 at one end of the rack member 27. The bell-crank 33 is fulcrumed, as at 35, to a bracket 36 causing the opposite bifurcated end 37 of the bell-crank 33 to move the shifting plate 21 20 through the medium of the pin 38 away from the end of the tank 1 thereby shifting the belt 17 from the fixed pulley 14 to the loose pulley 15 and belt 18 from the loose pulley 16 to the fixed pulley 14 which 25 reverses the movement of the rotatable clothes cylinder, or receptacle 4, as is manifest. When the rack member 27 has traveled its limit to the left, a reverse movement of the bell-crank 33 takes place due to the end of 30 the slot 34 engaging the end 32 of the bell-crank 33 causing the bell-crank 33 to move the shifting plate 21 toward the end of the tank, or tub 1 thereby causing the belt 17 to ride upon the fixed pulley 14 and the 35 belt 18 to ride upon the loose pulley 16.

The means for introducing air into the cylindrical clothes receptacle 4 from the bottom thereof will now be described.

39 indicates a suitable air cylinder suitably fixed to a bracket 40 which is suitably fixed to the tank, or tub 1. The cylinder 39 is provided with a suitable intake check valve 41 at its upper end and a suitable intake check valve at its lower end. Leading 45 from opposite ends of the cylinder 39 is an air delivery pipe 42, which pipe is provided with the suitable check valves 43 and 43'. A suitable piston 44 is arranged to reciprocate within the cylinder 39. A suitable piston rod 45 is suitably connected at its upper end to the lower end of the piston 44 and at its lower end to an eccentric pin 46 which is fixed to the pinion 10, as shown in Fig. 1.

55 The air delivery pipe 42 is connected at one end to the spindle 8. The spindle 8 is provided with a longitudinal passage 47. Communicating with the passage 47 is a vertical passage 48 extending upwardly from 60 the bottom surface of the spindle 8, as shown in Figs. 4 and 5.

49, 50, 51 and 52 indicate air delivery pipes, each having the multiplicity of air outlet openings 53. The air delivery pipes 65 are fixed in equal spaced relation to the

inner surface of the clothes receptacle 4 and act as rubbers. One end of each of the air delivery pipes 49, 50, 51 and 52 are closed and the opposite ends adjacent the spindle 8 have communication with the air 70 passages 54, 55, 56 and 57, respectively, of the bearing 7 so that each time the air passages 54, 55, 56 and 57 register with the vertical air passage 48 of the spindle 8 in the rotary movement of the clothes cylinder 4, 75 a charge of air under pressure will be forced into the perforated air discharge pipe in communication with the vertical air passage 48 causing the air to be directed upwardly against the clothes in the clothes cylinder 4 80 to loosen and cleanse the same, as is manifest. It will be observed that this action upon the clothes will be repeated four times during each revolution of the clothes cylinder, or receptacle 4.

85 Each end of the clothes receptacle 4 is provided with a multiplicity of openings 4' to permit the water within the tank, or tub 1 to enter the clothes receptacle 4, as shown.

90 In order to heat the water in the tank, or tub 1, I employ a plurality of suitable burners 58 connected to a suitable fuel feed pipe 59. Gas, oil, or gasoline may be used as the fuel for furnishing the heat to heat 95 the water within the tank 1.

95 The means for supporting and actuating a wringer will now be described.

100 60 indicates a driven shaft suitably supported under the tank 1 and provided at one end with a suitable gear 61 meshing with a suitable gear 62, which gear 62 is fixed to the loose pulley 16. A friction drive disc 63 is fixed to the opposite end of the driven shaft 60 and a driven disc 64 fixed to a 105 vertical shaft 65 is suitably held in contact with the driven disc 63.

110 The vertical shaft 65 is supported by means of a suitable bracket 66. The upper end of the vertical shaft 65 is square in cross section, and is receivable in a socket formed in the shaft 67 which is supported by means of the bracket 68. The upper end of the socket shaft 67 is provided with a bevel gear 69 adapted to mesh with a bevel gear 70 fixed to the shaft 71 of the lower roller 72 of the wringer 73. The upper roller 74 of the wringer is rotated in the usual manner, hence further explanation is thought unnecessary and superfluous. The 115 120 wringer 73 is supported upon a swinging arm 75 which is swingingly supported by means of the socket shaft 67.

125 76 indicates a suitable water drain pipe having a suitable valve 77.

When it is desired to actuate the wringer, the operator shifts the belt 18 through the medium of the belt guide lever 25 from the fixed pulley 14 to the loose pulley 16 while the belt 17 remains in engagement with the 130

loose pulley 15. This causes the loose pulley 16 to drive the gear 62 fixed thereto which gear meshing with the gear 61 revolves the wringer drive shaft 60. The 5 speed of the wringer is regulated through the medium of the friction driving plates 63 and 64, as is manifest.

The many advantages of the herein described invention will readily suggest themselves to those skilled in the art to which it appertains.

I do not desire to be understood as limiting myself to the exact details of construction and arrangement as herein described 15 and illustrated, as it is manifest that variations and modifications may be made without departing from the spirit and scope of my invention and the terms of the following claims, hence I wish it to be understood that I reserve the right to make any 20 such changes, or modifications as may fairly fall within the scope of the appended claims when fairly construed.

What I claim is:

25 1. In means for imparting alternate rotation to a clothes cylinder, a gear fixed to the cylinder, a driven shaft, a gear fixed to said shaft and meshing with said first mentioned gear, a pulley fixed to said shaft, a

pair of loose pulleys mounted upon said 30 shaft, a pair of drive belts for said pulleys running in opposite directions, a rack member, means for moving said rack member a predetermined distance in one direction, and means actuated by said rack member at the 35 end of its travel in either direction for shifting the belts to reverse the rotation of said driven shaft and meshed gears.

2. An alternating rotary mechanism for washing machines, consisting of a driven 40 shaft having a fixed pulley and a loose pulley positioned on opposite side of said fixed pulley, a pair of belts driven in opposite directions, a pinion fixed to said driven shaft, a gear in mesh with said pinion, a 45 rack member, means for supporting said rack member, means fixed to the gear for imparting movement in opposite directions to said rack member by the rotation of said gear and means actuated by said rack member at the completion of a full revolution 50 of the gear for shifting the belts to ride over the selected pulleys for controlling the direction of rotary movement of said gear.

In testimony whereof, I have hereunto 55 signed my name to the specification.

JOHN JOHNSON.
